Patented July 29, 1975

236,054

MOBILE BAR TABLE OR SIMILAR ARTICLE

Jonathan Ginat, New York, N.Y. (% A.C.I. Industries, Inc., 38-60 Review Ave., Long Island City, N.Y. 11100)

Filed Oct. 16, 1973, Ser. No. 406,820

Term of patent 14 years

Int. Cl. D6—03

U.S. Cl. D6—144

FIG. 1

FIG. 2

FIG. 1 is a perspective view of a mobile bar table showing my new design, with the lower table portion in closed position beneath the upper table portion.

FIG. 2 is a perspective view thereof wherein the table elements have been pivoted to alternate positions.

I claim:

The ornamental design for a mobile bar table or similar article, as shown and described.
